INTERLOCKING SYSTEM FOR RAILROADS

Sedgwick N. Wight, Rochester, N. Y., assignor
to General Railway Signal Company, Rochester, N. Y.

Application July 11, 1930. Serial No. 467,222

11 Claims. (Cl. 246—3)

This invention relates to manually controlled power operated interlocking systems for railroads, and more particularly to a system of remote control for a power operated switch machine, and is an improvement upon the invention disclosed in my earlier application Ser. No. 431,748 filed February 27, 1930.

5

In interlocking systems of the mechanically interlocked lever type, and types of systems in which the levers are locked by suitable approach locking or detector locking means, the operator is of course not able under unsafe conditions to move the lever, and for that reason cannot tentatively set up an operating condition which may 10 later become effective due to the clearing up of conditions which formerly locked the lever. In other words, in systems such as just mentioned, the operator cannot initiate a control until it is proper for switch control to become effective. In accordance with the present invention it is proposed to leave the levers unlocked at all times, and to provide such interlocking or approach or detector locking as may be required to be carried out electrically and irrespective of movement of 15 the lever, and in accordance with this invention it is proposed to provide simple electrical means for effecting approach and the detector locking control, which requires movement of the control lever while the approach and detector locking device is energized and ineffective, and this is carried out without mechanically restraining the movement of the control lever. Another object 20 of the present invention is to provide a simple and novel organization of parts and circuits to obtain the necessary and desirable indications and safe controllability of a power operated switch and its associated signals.

More specifically it is proposed to control the distant traffic controlling device, such as a switch machine, through the medium of a snap action or stick type relay, and to provide suitable time limiting means associated with the lever in such a way that the lever may control the snap acting relay only for a short period of time after each 25 operation thereof, so that if energy is prevented from flowing to such snap acting relay by reason of approach or detector locking the snap acting relay cannot operate when the approach and detector conditions clear up, even though the lever 30 is left in the operated position.

Other objects, purposes and characteristic features of the present invention will in part be obvious from the accompanying drawing and will in part be more specifically described hereinafter.

55 In describing the invention in detail reference

will be made to the accompanying drawing, in which the portion in the dotted rectangle represents the apparatus located in the interlocking tower, and the remaining apparatus illustrated is located at a distant track switch on the railway system.

Structure

Referring to the drawing, the track rails 1 of the railway system have been shown divided 60 into blocks by insulated joints 2, to provide track circuits of which the detector track circuit having track relay DR and a track battery 3, and the approach track section having a track relay TR and a track battery 4, only have been shown. The 65 siding or diverging route has been indicated by track rails 5 connected to the main track through the medium of a track switch S, which track switch is operated by a switch machine SM. This switch machine SM is controlled by the snap 70 action, or stick type relay CR, which relay after it is operated to one of its operated positions remains there until it is operated to the other position, even though it is deenergized in the meantime.

In the interlocking tower T, conventionally shown by the dotted rectangle T, is located a lever L, having pole changing contacts 10 and 11, which contacts 10—11 supply current of one polarity or the other to the relay CR, providing 75 the lock relay LR is energized. This lock relay LR can only be temporarily energized, because its energizing circuit includes a back contact 12 of the relay SR, and the relay SR is energized when the line relay LR is energized, so that the lock 80 relay LR may at any time only be energized until it has picked up and has again energized the stick relay SR, which stick relay when up opens its contact 12 and effects deenergization 85 of the lock relay LR. Deenergization of the lock 90 relay LR is also dependent on the detector and conflicting route locking relay DL, which has an energizing circuit including front contacts 13 and 14 of the track relays TR and DR, respectively.

100 Although suitable interlocking and detector locking and approach locking for the switch machine SM may be made locally and outside of the tower T itself, suitable electric interlocking may be provided whereby the lever L will not be effective to control the switch machine SM unless the signals of all conflicting routes are in their stop position, and all approach track circuits to the switch machine or other traffic controlling device are unoccupied, and the like. Apparatus 105 110

for this purpose has been conventionally shown by the front contact 16 of the detector and conflicting route locking relay DL from which it appears that the lock relay LR can only be energized after the signals of all conflicting routes assume the stop position and after all approach sections to the switch S are unoccupied. In this connection it is to be understood that the contact 17 in some cases comprises a contact on a signal which is closed only when the signal is in the stop position. In order to get a more clear understanding of the features of the system, the essential apparatus of which only has been illustrated, the remaining apparatus such as indicating lamps indicating the condition of way-side signals and the switch machine and the occupancy of various track circuits having been omitted, it is believed expedient to consider the operation of the system.

Operation

Let us assume that the operator in the tower T wishes to operate the switch machine SM to the take-siding position, and in order to do so operates the lever L to the dotted position. This movement of the lever reverses the potential applied to the stick relay SR, so that the current flow in the winding of the stick relay SR and the flux resulting therefrom must reverse, and the relay SR is so designed that it will assume its deenergized position in response to this reversal of flux in the core of the relay SR. With this stick relay SR once deenergized and its stick contacts 20 open, it will remain deenergized until either the back contact 21 of the relay DL or the front contact 22 of the relay LR is closed. With the stick relay SR deenergized, and on the assumption that there is no approaching train and the track relays TR and DR are energized, and also on the assumption that none of the conflicting signals assume the clear position, as manifested by the contacts 17 when assuming the closed position, the lock relay LR is energized through the following circuit:—beginning at the terminal B of a suitable battery, front contact 16 of the relay DL, wire 23, back contact 12 of the relay SR, wire 24, winding of the relay LR to the other terminal C of said battery.

With lever L now assuming the dotted position and with the lock relay LR energized the control relay CR may be operated to the reverse dotted position through the following circuit:—beginning at the positive terminal of the battery 25, wire 26, contact 10 of the lever L, wires 28 and 29, front contact 30 of the relay LR, line wire 31, winding of the relay CR, line wire 32, front contact 33 of the relay LR, wires 34 and 35, contact 11, wire 36, and back to the negative terminal of the battery 25. The circuit just traced need only be closed momentarily to effect operation of the control relay CR, and operation of the control relay CR to the dotted position effects operation of the switch machine SM to the take-siding position, through the medium of the reverse wire R included in a circuit readily traced in the drawing.

With the lock relay LR energized the stick relay SR is picked up through the following circuit:—beginning at the positive terminal of the battery 25, wire 26, lever contact 10, wires 28, 40, 41 and 42, front contact 22 of the lock relay LR, wires 43, 44 and 45, winding of the relay SR, wires 46 and 35, contact 11 of the lever L, wire 36, and back to the battery 25. The closure of this circuit will pick up the stick relay SR, as a

result of which the stick contact 20 will shunt the contact 22, so that this relay SR remains energized through a stick circuit readily traced in the drawing even though the relay LR drops and its contact 22 opens. Picking up of the stick relay SR breaks the energizing circuit of the lock relay LR at the back contact 12 of this stick relay SR, so that the lock relay LR is again deenergized after a very short period of time, and with the contacts 30 and 33 assuming their retracted position the line wires 31 and 32 are shorted together through the shunting wires 46 and 47.

It is thus seen that operation of the lever under normal favorable route and traffic conditions will allow the lock relay LR to be energized only for a short time, depending on the drop-away characteristic of this lock relay LR, and it may be pointed out here that the lock relay LR is preferably slow dropping, so that its contacts remain up for say one or two seconds, and that thereafter the line circuit to the control relay CR is again broken and is shorted by the wires 46 and 47, so that the application of current from an unauthorized source will be unable to operate the control relay CR.

Let us now assume that the operator wishes to operate the switch machine SM at a time when the approach and route relay DL is deenergized. In this case operation of the lever L will effect deenergization of the stick relay SR, but this stick relay will remain deenergized only for an instant, because its stick contact 20 is shunted by the back contact 21 of the approach and route relay DL, so that, if thereafter the approach and route relay DL picks up, the control relay CR will not be operated, because the stick relay SR is energized and its contact 12 prevents energization of the lock relay LR.

It is thus seen that operation of the lever L to operate the switch machine SM is only effective to operate such switch machine if such lever is operated under non-conflicting route and favorable traffic conditions insofar as the movement of a train toward the track switch S is concerned. In other words, the effect of moving the lever L is temporary, and corresponds in this respect to a lock lever in that the attempt to operate a locked lever when it is improper to operate such lever has no effect upon the future control exercisable by such lever. Furthermore, the time period through which movement of the lever L is effective to control the distant control relay CR is independent of the rapidity at which the lever is moved from one position to the other, this because the stick relay SR is dropped by reversal of polarity of the current applied thereto rather than by momentary deenergization of the relay, and this stick relay SR assumes its deenergized condition in response to each operation of the lever L from one extreme to the other extreme position.

It is of course understood that the contact 17, which may comprise any number of contacts in series each of which is closed when the signal it represents is at stop, may be omitted from the circuit of the detector and route relay DL, such protection when the contacts 17 are omitted being obtainable locally, either through the medium of the control relay CR or through the circuits for controlling the switch machine SM, by suitable checking contacts closed only when the signals of conflicting routes are at stop.

Also, if desired, front contacts of the relay SR may be included in the wires 29 and 34, so that relay CR is not controllable by the lever L if the

- relay SR is deenergized by reason of an unauthorized break in its energizing circuit, the drop-away period of the relay LR allowing sufficient time to control the relay CR.
- 5 The hands-off signal HO, preferably comprising a signal lamp, is energized when the detector and route relay DL is in its deenergized condition, so that the operator is at all times advised whether he may expect any results to be obtained 80
- 10 from the operation of his lever L, this since for reasons heretofore given operation of the lever L at a time when this relay DL is deenergized is of no avail, and the control relay CR is not operated by the lever L under this condition. Obviously, instead of employing the hands-off signal lamp HO, a lamp illuminated only when the detector and approach relay DL are deenergized may be employed in which event the illumination 85
- 15 of such signal lamp will tell the operator that there is no electric locking or means preventing control of the control relay CR by the lever L.
- Having thus shown and described one specific embodiment of the present invention, it is desired 90
- 20 to be understood that the particular embodiment illustrated has been selected for the purpose of facilitating disclosure of the principles of the invention and the functions desired to be carried out thereby, and it is further to be understood 95
- 25 that various other expedients for obtaining the same results may be employed, and other additions and modifications may be made to the disclosure illustrated, without departing from the spirit or scope of the present invention, except 100
- 30 as demanded by the scope of the following claims.
- 35 What I claim as new is:—
1. In an interlocking system for railroads; the combination with a traffic controlling device; of a free mechanically non-lockable lever having 105
- 40 two extreme positions for controlling such traffic controlling device to corresponding extreme positions; means for preventing said traffic controlling device being controlled by said lever under unfavorable conditions; and other means for permitting control of said traffic controlling device by said lever which requires movement of said lever simultaneously with favorable traffic conditions comprising; a normally energized stick relay, and a pick up circuit for said stick relay 110
- 45 closed under unfavorable traffic conditions.
2. In an interlocking system; the combination with a traffic controlling device; of a free lever for controlling such traffic controlling device; means for preventing said traffic controlling device being controlled by said lever under unfavorable conditions; and other means for permitting control of said traffic controlling device by said lever which requires movement of said lever when traffic conditions are favorable comprising; a time element device operated in response to operation of said lever irrespective of the time consumed during operation of said lever and effective 115
- 50 for a time only.
3. In an interlocking system; the combination with a normally inactive traffic controlling device; of a free lever for rendering such traffic controlling device active; means for preventing said traffic controlling device being rendered active by said lever under unfavorable conditions; and other means for permitting said traffic controlling device to be rendered active by said lever which requires the act of movement of said lever to occur when traffic conditions are favorable comprising; a 120
- 55 normally energized stick relay which is dropped by operation of said lever and is restored under unfavorable traffic conditions.
4. In an interlocking system; the combination with a traffic controlling device; of a free lever for controlling such traffic controlling device but by itself ineffective to permit said traffic controlling device to be controlled by said lever; and other means for permitting control of said traffic controlling device by said lever which requires movement of said lever simultaneously with favorable traffic conditions comprising; a slow acting relay which if energized permits control of said traffic controlling device by said lever, and a normally energized stick relay for controlling said slow acting relay having a pick-up circuit including a front contact of said slow acting relay and having a stick circuit including contacts of said lever.
5. In an interlocking system; the combination with a traffic controlling device; of a free lever for controlling such traffic controlling device, but normally ineffective to directly control said traffic controlling device; and other means for permitting control of said traffic controlling device by said lever which to be effective requires movement of said lever when traffic conditions are favorable comprising; a slow acting relay which if energized permits control of said traffic controlling device by said lever, a normally energized stick relay having a stick circuit including pole changer contacts controlled by said lever and a stick contact of said stick relay, a back contact of said stick relay included in the energizing circuit of said slow acting relay, and a front contact of said slow acting relay shunting 125
- 60 said stick contact, whereby movement of said lever reverses the direction of current flow in said stick relay and effects dropping of the same and picking up of said slow acting relay effects reenergization of said stick relay and deenergization of said slow acting relay.
6. In an interlocking system; the combination with a traffic controlling device; of a free lever for controlling such traffic controlling device but normally ineffective to directly control said traffic controlling device; and other means for permitting control of said traffic controlling device by said lever which to be effective requires movement of said lever when traffic conditions are favorable comprising; a slow acting relay which if energized permits control of said traffic controlling device by said lever, a normally energized stick relay having a stick circuit including pole changer contacts controlled by said lever and a stick contact of said stick relay, a back 130
- 65 contact of said stick relay and a traffic controlled contact included in the energizing circuit of said slow acting relay, and a front contact of said slow acting relay shunting said stick contact, whereby movement of said lever reverses the direction of current flow in said stick relay and effects dropping of said stick relay and picking up of said slow acting relay providing said traffic controlled contact is closed picking up of which slow acting relay in turn effects reenergization of said stick relay and deenergization of said slow acting relay.
7. In an interlocking system; the combination with a traffic controlling device; of a free lever for controlling such traffic controlling device but normally ineffective to directly control said traffic controlling device; and other means for permitting control of said traffic controlling device by said lever which other means to be effective requires movement of said lever when traffic 135

- conditions are favorable comprising; a slow acting relay which if energized permits control of said traffic controlling device by said lever, a normally energized stick relay having a stick circuit including pole changer contacts controlled by said lever and a stick contact of such stick relay, a lock relay which is energized if traffic conditions permit operation of said traffic controlling device, a back contact on said stick relay 5 and a front contact on said lock relay included in series in said slow acting relay, and a front contact of said slow acting relay shunting said stick contact, whereby said stick relay is deenergized upon reversal of said lever and is picked up after a short period of delay. 10
8. In an interlocking system; the combination with a traffic controlling device; of a free lever for controlling such traffic controlling device but normally ineffective to directly control said traffic controlling device; and other means for permitting control of said traffic controlling device by said lever which to be effective requires movement of said lever when traffic conditions are favorable comprising; a slow acting relay 15 which if energized permits control of said traffic controlling device by said lever, a normally energized stick relay having a stick circuit including pole changer contacts controlled by said lever and a stick contact of such stick relay, a lock 20 relay which is energized if the signals of conflicting routes are at stop and traffic conditions permit operation of said traffic controlling device, a back contact on said stick relay and a front contact on said lock relay included in series 25 in the circuit of said slow acting relay, a front contact of said slow acting relay and a back contact of said lock relay each shunting said stick contact, whereby said stick relay is deenergized upon reversal of said lever and is immediately 30 picked up if said lock relay is deenergized but is picked up after a short period of delay if said lock relay is energized. 35
9. In combination, a distant traffic controlling device; a two position relay constructed to respond to a momentary flow of current and to remain in its last operated position until operated to another position for controlling said device; a lever for controlling said relay but normally ineffective to directly control said relay; and means for permitting control of said two position relay by said lever including, a slow acting relay having front contacts included in the circuit of said two position relay, and a stick relay controlled by said lever for energizing said slow acting relay for a time in response to the act of changing the position of said lever. 40
10. In combination; a railway traffic controlling device having a normal and an abnormal condition; a free lever operable to two extreme positions and tending when in one position to cause said traffic controlling device to be operated to the normal condition and when in the other position tending to cause said traffic controlling device to be operated to the abnormal condition; traffic controlled means for preventing said lever from controlling said traffic controlling device so long as traffic conditions are unfavorable; and other means for preventing said lever from controlling said traffic controlling device in response to clearing up of said unfavorable traffic conditions unless said lever is operated after such clearing up of traffic conditions comprising; a slow acting relay, and a stick relay controlled by said lever and by said slow acting relay and in turn controlling said slow acting relay. 45
11. In combination; a railway traffic controlling device having a normal and an abnormal condition; a free lever operable to two extreme positions and tending when in one position to cause said traffic controlling device to be operated to the normal condition and when in the other position tending to cause said traffic controlling device to be operated to the abnormal condition; and other means for preventing control of said traffic controlling device by said lever under certain traffic conditions and thereafter irrespective of traffic conditions unless said lever is operated after traffic conditions have again changed comprising; a slow acting relay, and a stick relay controlled by said lever and by said slow acting relay and in turn controlling said slow acting relay. 50

SEDGWICK N. WIGHT.
